CLAIM

The ornamental design for image scanner for automated fingerprint identification system, as shown and described.

DESCRIPTION

FIG. 1 is a front elevational view of a fingerprint identification machine showing our new design;

FIG. 2 is a rear elevational view thereof;

FIG. 3 is a right side elevational view thereof, the opposite side being a mirror image thereof;

FIG. 4 is a top plan view thereof;

FIG. 5 is a bottom plan view thereof; and

FIG. 6 is a top, front perspective view thereof on a reduced scale.

FIG. 1

FIG. 2

FIG. 4

FIG. 5

FIG. 3

FIG. 6
